UNITED STATES PATENT OFFICE

93,848

DESIGN FOR A HANDLE OR SIMILAR ARTICLE

Kurt Rettich, Grand Rapids, Mich., assignor to
Keeler Brass Company, Grand Rapids, Mich.

Application July 16, 1934, Serial No. 52,601

Term of patent 3½ years

To all whom it may concern:

Be it known that I, KURT RETTICH, a citizen of the United States, residing at the city of Grand Rapids, in the county of Kent, and State of Michigan, have invented a new, original, and ornamental Design for a Handle or Similar Article, of which the following is a specification, reference being had to the accompanying drawing, forming a part thereof.

Fig. 1 is a front perspective view, and

Fig. 2 is a rear perspective view showing my new design, the dominant feature of which is the three recessed panels which may be plain, black, or any other color, with the higher and lower panels terminated by the laurel leaf.

I claim:

The ornamental design for a handle or similar article as shown and described.

KURT RETTICH.
